UNITED STATES PATENT OFFICE.

WILLIAM L. SAUNDERS, OF JERSEY CITY, NEW JERSEY.

DRILL-HEAD FOR CHANNELING-MACHINES.

SPECIFICATION forming part of Letters Patent No. 311,378, dated January 27, 1885.

Application filed November 17, 1884. (No model.)

To all whom it may concern:

Be it known that I, WILLIAM L. SAUNDERS, a citizen of the United States, residing at Jersey City, in the county of Hudson and State of New Jersey, have invented certain new and useful Improvements in Drill-Heads for Channeling-Machines, of which the following is a specification, reference being had to the accompanying drawings.

10 My invention relates to the class of machinery used in channeling stone, where an open cut or channel is made by the intermittent blows of a gang of drills mounted upon a car and fed in the direction of the cut.

15 It consists in an improved means for locking the gang of drills more firmly and securely in their clamp, which is permanently secured to the reciprocating cross-head, and in the combination and arrangement of parts, as hereinafter more fully described, claimed, and illustrated in the accompanying drawings, forming part of this specification.

20 In machines of this class now in use considerable difficulty has been experienced in securing the drills to the cross-head, the blows of the engine serving to dislodge and disarrange them, and it is not an unfrequent occurrence for them to be entirely displaced. It is also, now, a matter requiring considerable time 25 and consequent stoppage of the machinery to renew the drills in such a gang for sharpening or other purposes; but by means of the present invention a gang can be locked in place by one blow of a hammer.

30 The manner of fastening in my improved device is such that various lengths of drills can be locked in the same head, and it is also capable of holding a gang of drills set in progressive series, so that their cutting-edges 35 shall form a line oblique to the direction of reciprocation. This oblique setting of the drills is necessary in doing transverse or side-hill cutting where the engine and drills are set at an angle, the points remaining on a line 40 parallel with the track.

45 In machines where a gang of drills is employed it is usual to hold the drills by two clamps, one being an upper clamp with serrations to correspond with serrations on the 50 face of the drills. This clamp serves to maintain the points in a fixed position with reference to each other. The other catches the

body of the drills and gives the gang the reciprocating motion. Another form of clamp is where the tops of the drills abut against a shoulder in the clamp, thus necessitating drills of equal length. By my device the upper clamp, with its serrated drills, is done away with, and I accomplish the binding of the drills together by the powerful edge-pressure 55 imparted through the key. I can also use drills of varied lengths. It is obvious that the harder the blow driven by the machine, the tighter the drills get in the clamp.

I attain the several ends in view by means 60 of mechanism illustrated in the drawings hereto attached, in which—

Figure 1 is an elevation of the head, with a gang of drills clamped therein. Fig. 2 is a similar view showing the drills adjusted to 65 angular cutting. Fig. 3 is a plan view of Fig. 1. Fig. 4 is a section on the line 4 4 of Fig. 2, with the drills removed. Fig. 5 is a side elevation showing the head and drills connected to the machine.

70 The same reference-letters have been applied to similar parts throughout the several figures.

In the drawings, A represents a gang of drills, placed side by side, and clamped in the 75 head B. This head is locked to the piston-head P by means of bolts Q, in connection with the lip or shoulder L on said head B, which lip extends a short distance beneath the piston-head P and receives part of the shock, 80 thereby lessening the strain upon the bolts Q.

85 The manner of clamping the gang of drills in the head is as follows: In the rear face of the head is a depression of any desired width, and of a depth slightly less than the thickness 90 of the drills. One edge of this depression, 1 2, is cut obliquely, and the other edge, 5 6, obliquely, also, but on twice the angle of the first. The outside drills of every gang have one beveled face on the same angle as the edge 95 1 2. It will thus be seen that when the gang is placed in position one outside drill, being beveled as described, rests squarely against the oblique edge 1 2, but the other presents a face, 3 4, not parallel with its corresponding edge, 5 6. Into the angular space thus formed I drive the wedge W, which is of a thickness 100 equal to the difference between the angles of the oblique surfaces 3 4 and 5 6. When it is

desired to make up the gang of a smaller number of drills, I substitute for the wedge W another and similar one, the body of which is larger, but the angles of the side of which are 5 still the same.

In Fig. 2 I have shown the manner of locking the drills when adjusted to angular cutting. In this event the wedge is slipped farther up or down conversely with the direction 10 its adjacent drill may be moved in order to give the desired angle to the cutting-edges of the gang.

My device is simple and inexpensive in construction and effective in operation, locking 15 the drills firmly in a position opposed to the blows of the piston, which thus tends to hold them in position and prevent their displacement. They are thus rendered capable of 20 speedy and perfect adjustment to any angle of cut.

It is obvious that its use necessitates the employment of two drills in each gang with one beveled face each, but otherwise the ordinary flat drill as now employed for channeling may 25 be used, and their length is a matter of no consequence within certain limits, as a gang may be composed of the desired number of drills, all of different lengths.

I claim as my invention—

1. In a reciprocating drill, the head B, having 30 drill-receiving depression or recess in the side thereof, said recess being formed with a longitudinal plane surface, against which the drills rest, and beveled ends between which the said drills are secured, in combination 35 with one or more drills having beveled outer faces and the removable wedge W, as described.

2. In a reciprocating drill, a head having 40 drill-receiving recess or depression terminating in differentially-beveled ends, in combination with one or more drills, A, and the removable wedge W, as described.

3. In a reciprocating drill, the head B, having 45 drill-receiving depression with differentially-beveled ends formed with the lip L, in combination with one or more drills, A, having beveled outer faces, and the wedge W, as described.

In testimony whereof I affix my signature 50 in presence of two witnesses.

WILLIAM L. SAUNDERS.
